(57) **CLAIM**

The ornamental design for a ring setting, as shown and described.

DESCRIPTION

FIG. 1 is a front side elevation of my new design for a ring setting;

FIG. 2 shows a back side thereof;

FIG. 3 is a left side thereof;

FIG. 4 is a right side thereof;

FIG. 5 is a top view thereof;

FIG. 6 is a bottom view thereof;

FIG. 7 is a side perspective view thereof; and,

FIG. 8 is a bottom perspective view thereof.

The broken lines shown illustrate environmental structure and form no part of the claimed design.
